FLUORESCENT LAMP FIXTURE FOR RIPENING PRODUCE OR SIMILAR ARTICLES

Hendrik A. J. de Vos, Wenham, Ruth E. Petersen, Medfield, and John J. Vefere, Beverly, Mass., assignors to Sylvania Electric Products Inc., a corporation of Delaware

Filed June 2, 1967, Ser. No. 7,343

Term of patent 14 years

(Cl. D48—20)

FIG. 1

FIG. 2

FIG. 3

FIG. 4

FIG. 5

FIGURE 1 is a side perspective view of a fluorescent lamp fixture for ripening produce or similar articles showing our new design.

FIGURE 2 is a side elevational view of the fluorescent lamp fixture for ripening produce or similar articles.

FIGURE 3 is a side elevational view of the other side of the fluorescent lamp fixture for ripening produce or similar articles.

FIGURE 4 is a plane view of the top of the fluorescent lamp fixture for ripening produce or similar articles shown in FIGURE 1.

FIGURE 5 is a plane view of the bottom of the fluorescent lamp fixture for ripening produce or similar articles shown in FIGURE 1.

We claim:

The ornamental design for a fluorescent lamp fixture for ripening produce or similar articles, as shown and described.
